UNITED STATES PATENT OFFICE

LOUIS GEORGE COPIES, OF BAYONNE, NEW JERSEY

PAINT STIRRER

Application filed April 22, 1927. Serial No. 185,773.

My invention is a stirrer for agitating paint in containers, the object being to facilitate the operations of stirring the pasty mass at the bottom of a can, and of mixing such 5 pasty mass with the liquid contents of said can, to the ultimate end that the paste and liquid can be thoroughly mixed together to produce a paint of the desired consistency, whereby the operations can be performed in less time and with less effort than is possible 10 with the common "paint paddle", so-called, ordinarily supplied by the trade to customers.

My invention is embodied in a hand stirrer of the kind known as a paddle, but in contradistinction to the ordinary solid slab of wood 15 used for this purpose, I construct the stirrer with slots for the performance of the function of reducing the resistance to the movement of the stirrer when the latter is thrust 20 with a downward motion into the pasty mass at the bottom of the container, and, also, when the stirrer is moved by hand pressure through said mass.

It is well known that commercial paint, 25 enamel, lacquers, or the like, when packed in cans or other containers and allowed to stand undisturbed for an appreciable length of time, results in an accumulation of pigments or other ingredients in the bottom of the container and such accumulation attains a pasty 30 condition below the liquid ingredient or ingredients. This pasty mass must be incorporated with the liquid, and the problem has been to devise a simple, effective and economical 35 stirrer which can be used by hand for easily and quickly breaking up the pasty mass, and for mixing therewith the liquid contents of the container.

According to my invention, the stirrer is a 40 blade slotted in a particular manner to produce a comb-like formation, the function of the slots being primarily to reduce the resistance to the movement of the stirrer through the pasty mass at the initial stages of the mixing 45 operation, and the utility of the particular formation of the slots being to act upon all the body of the mass within the field of action of the blade. This utility will be appreciated when it is understood that slots cut 50 in the stirrer at a right angle to the face of

said stirrer will, in the movement of the stirrer through the mass, leave trails of undisturbed paste on the bottom of the paint can, but to eliminate this objection, while retaining the desirable quality of relatively 55 free movement through the mass, I construct the stirrer with slots positioned at an angle to the face of the stirrer, with the result that the slots constitute a comb-like formation at one end of the stirrer, and the fingers of such 60 comb are beveled, the angle of inclination to the face of the stirrer being such that the fingers sweep through the pasty mass without leaving traces of such mass undisturbed on the can bottom. Again, the stirrer is 65 fashioned with oppositely inclined slots producing a comb-like formation which imparts to the stirrer the function of moving in a prescribed path and without a tendency to become deflected to one side or the other by 70 unequal resistance from the pasty mass.

In service, my stirrer at the start of the operation is thrust by a downward motion through the liquid and into the pasty mass at the bottom of the container, and then is 75 moved in a horizontal direction, or substantially so, through such mass, the effect at the start being to cut grooves in the mass and open up such mass to the free entry into such 80 grooves of the liquid present in the can, and by repeated movements of the stirrer, the pasty mass is broken up easily and quickly with the result that the pigments and the liquid are thoroughly mixed together by a 85 minimum of effort on the part of the workman and with a material saving of time.

Other functions and advantages of the invention will appear from the following description, taken in connection with the accompanying drawings, wherein—

Figure 1 is a perspective view of a paint stirrer embodying the invention.

Figure 2 is a view in side elevation.

Figure 3 is a horizontal cross section on the line 3—3 of Figure 2, and on an enlarged 95 scale.

In the practical embodiment of the invention shown in the drawings, the stirrer A comprises a substantially oblong blade the 100 novel feature of which is a comb-like forma-

tion at one end of said blade. The material and the dimensions of the stirrer are not vital factors, although it may be stated that the paddle consists usually of wood, but for certain classes of work, metal, fibre, hard rubber, celluloid, or any other material may be used in the production of the article.

For convenient manipulation, the stirrer is fashioned at the end opposite the comb-like formation with a handle, *a*, of suitable form, but the body of the paddle is of suitable length, and with flat faces and edges.

The comb-like formation is imparted to an end portion of the paddle by the presence of slots which open through the bottom end and through the opposite faces of said paddle, but to equalize the resistance to the motion of the paddle through the materials these slots are inclined oppositely, substantially as shown in Figure 3. The slots are indicated at *b*, *c*, with the slots *b* inclined in one direction to the faces of the paddle, whereas slots *c* are inclined oppositely to slots *b* and to the faces of said paddle. The slots produce fingers *B*, *C*, *D*, constituting the comb-like formation at one end of the stirrer, whereof the finger *D* is at the middle of the paddle and the opposite edges of said middle finger are reversely inclined, being bounded by the adjacent oppositely inclined slots *b*, *c*. The fingers *B*, *C*, at the respective side edges of the stirrer are each bounded in part by oppositely inclined slots *b*, *c*, and in part by the straight surfaces at the faces and marginal portions of the paddle, whereas the fingers *B*, *C*, which are intermediate the middle finger *D*, and the described side fingers *B*, *C*, are bounded by the reversely inclined slots *b*, *c*, and by the flat faces at the opposite sides of the paddle.

The angle of inclination of the slots is such that there is a slight overlap at the edges of the fingers viewed from the faces of the stirrer, and when so viewed by the eye, no light can be seen through the slots. The angle should be such that there is just sufficient slant in the slot to cut off the view; obviously, too great an angle is to be avoided because inimical to the easy flow of paste through the slots. The width of the slots is a material factor, although in different sizes of paddles the width may vary from one-sixteenth to one-eighth of an inch.

To use the stirrer, the can is opened as usual, and the handle *a* of the stirrer is grasped in one hand, and the stirrer is thrust by a downward motion, with the comb-like formation foremost, into the contents of the can. At this initial movement, the fingers pass through the pasty mass at the bottom of the can, the slots affording spaces into which may flow the paste which is dislodged by the entry of the fingers, and thus the slots reduce the resistance to the entry of the paddle into the pasty mass. The stirrer is now moved by hand in a substantially horizontal direc-

tion, with the result that the fingers cut grooves in the pasty mass, into which grooves the liquid present in the can is free to flow. During such horizontal movement of the stirrer, the pasty mass passes through the slots, the inclination of which and the corresponding bevel of the fingers so acts upon the mass as to allow no part of said mass within the range of the paddle to remain undisturbed, and thus all the paste within the field of action of the paddle is stirred, with the result that the operation of stirring is facilitated to a marked extent and a thorough uniform admixture of the semi-solid and liquid ingredients is obtained with a minimum of effort by the workman.

The inclined slots perform important functions in my paddle, and the opposite inclination of said slots lend an additional function. The mere presence of slots in the comb-like formation tends to reduce the resistance by the pasty mass to the movement through it of the paddle, but the inclination of the slots lends to the paddle the quality of stirring up all the mass within the field of action of the paddle, and, moreover, the opposite inclination of said slots tends to equalize the resistance of the mass to the motion through it of the paddle, with the result that there is no appreciable inequality in the resistance at the respective edges of the paddle and it follows that the paddle is not deflected in its travel, but is free to follow a determined path.

My device is simple in construction, economical of manufacture, and experience shows that it is markedly efficient in service for the reason that it affords means whereby all the paint in a can is thoroughly and uniformly mixed in less time and with less effort than is possible with the ordinary solid paddle.

Obviously, the stirrer can be made in different sizes suited to the work to be performed, and the principle of the stirrer can be used in other relations, such as in vats or tanks of large size the stirrers or scrapers of which require power for their operation.

In the preferred form of my invention the comb-like formation at one end of the blade is secured by slots extending at an angle to the faces of said blade, or as it may be otherwise stated, the slots are at an angle to the longitudinal axis of the blade. While the angular disposition of the slots is desirable for the functions recited, it is appreciated that in some circumstances I may provide the comb-like formation by the use of slots cut through the blade at a right angle to the faces of the blade, and parallel to the axis of the blade, but as such parallel relation will be readily understood, I have not deemed it necessary to illustrate the same in the drawings.

By reference to the drawings, it will be noted, furthermore, that the body portion

of the stirrer is imperforate above the comb-like formation, and that the slots open or extend through the lower end of said stirrer. The open ended slots are advantageous for the reason that the comb-fingers are thrust easily into the pasty mass at the bottom of the can by the initial downward motion of the stirrer. The imperforate body above the comb exceeds in area the length and width of the comb-like formation, and such imperforate part of the stirrer acts on the ingredients of the paint to stir them and to facilitate their admixture.

Having thus fully described my invention, 15 What I claim as new and desire to secure by Letters Patent is:—

As a new article of manufacture, a stirring paddle comprising a body provided with a handle portion at one end and a comb-like structure at the opposite end, the major portion of the body between the handle and the comb-like structure being of substantially the same width as the comb-like structure and imperforate to secure a paddle action on the liquid content of a container, said comb-like structure having a plurality of similar opposite longitudinally extending slots inclined at an angle to the vertical sides of the body so as to form angular central and side fingers 25 adapted for ready entry into the semi-solid stratum at the bottom of the paint container, the walls of the slots being in overlapped relation to enable the angular fingers to stir and agitate the semi-solid paint component 30 35 lying in the path of the paddle and the slots converging to cause a commingling of the material passing through the slots and the side fingers producing a free balanced movement with uniform pressure at each side of the paddle.

In testimony whereof I have hereto signed
my name this 21 day of April, 1927.
LOUIS GEORGE COPEs.
